UNITED STATES PATENT OFFICE.

HANNA E. SMITH, OF WILLIAMSPORT, PENNSYLVANIA.

DESIGN FOR A BRUSH.

46,754.

Specification for Design.

Patented Dec. 8, 1914.

Application filed September 25, 1914. Serial No. 863,563. Term of patent 7 years.

To all whom it may concern:

Be it known that I, HANNA E. SMITH, a citizen of the United States, residing at Williamsport, in the county of Lycoming and State of Pennsylvania, have invented a new, original, and ornamental Design for Brushes, of which the following is a specification, reference being had to the accompanying drawing, forming a part thereof.

Figure 1 is a perspective view of a brush, showing my new design; and Fig. 2 is a front elevation thereof.

I claim:

The ornamental design for a brush, as shown.

HANNA E. SMITH.

Witnesses:

A. H. STEAD,

H. C. VINCENT.
